United States Patent Office

Des. 185,355
Patented June 2, 1959

185,355

STATUETTE

Alfred John Flauder, Trumbull, Conn.

Application December 31, 1958, Serial No. 54,006

Term of patent 7 years

(Cl. D29—23)

Fig. 1 is a front elevational view of a statuette, showing my new design;

Fig. 2 is a left side elevational view, thereof;

Fig. 3 is a rear elevational view thereof of Fig. 1; and
Fig. 4 is a right side elevational view, thereof.

I claim:

The ornamental design for a statuette, substantially as shown.
